UNITED STATES PATENT OFFICE.

FREDERICK W. BROWN, OF CAMBRIDGEPORT, MASSACHUSETTS.

DRESS-FORM.

SPECIFICATION forming part of Letters Patent No. 400,297, dated March 26, 1889.

Application filed November 12, 1888. Serial No. 290,569. (No model.)

To all whom it may concern:

Be it known that I, FREDERICK W. BROWN, a citizen of the United States, residing at Cambridgeport, in the county of Middlesex and 5 State of Massachusetts, have invented certain new and useful Improvements in Dress-Forms; and I do declare the following to be a full, clear, and exact description of the invention, such as will enable others skilled in the art to 10 to which it appertains to make and use the same, reference being had to the accompanying drawings, and to the letters and figures of reference marked thereon, which form a part of this specification.

15 Figure 1 is a vertical section of a dress-form as made in accordance with my invention. Fig. 2 is a sectional elevation of a portion of the skirt-frame and standard. Fig. 3 is a horizontal section of the form taken on line 3 20 3 of Fig. 1. Fig. 4 is a perspective view of the collar C and its arms and also two of the arms D.

My invention consists in a new construction and arrangement of parts whereby the 25 form can be adjusted to the different sizes required; and, furthermore, the different parts of the form are so connected that they can be readily detached from each other, so as to admit of being packed together into a space of 30 about one-fourth of the size occupied by the form when set up for use, as hereinafter described, and particularly pointed out in the claims.

In the drawings, A denotes the standard, 35 made in sections a b c, of tubing, the former of which screws into the foot B. The section b slides within the section a, and its height is regulated by a movable collar, d, confined to said section by a set-screw, e, said collar resting on the top of the section a in the usual manner. The section c enters the top of the section b, and fits thereto with a tight joint, it having a shoulder, f, to rest on the top of said section. Near to the top of the section b 40 is fixed a collar, C, provided with slotted arms h, there being as many of said arms as there are sections to the form. Each arm h, at its outer end, has an upwardly-extending projection, i, which is to enter either of the 45 slots in an extension-arm, D, at the inner end 50 of which is a downwardly-extending projec-

tion, k, which enters either of the slots of the arm h beneath it at the same time that the projection i enters a slot in the said arm D, and when the latter arm rests on the arm h 55 55 the two will be firmly connected to each other by means of the projections and slots. From the outer end of each arm D there extends upward a projection, l, which enters a socket, m, projecting from the inner surface of the 60 waistband of each skirt-section E and sustains the said sections, as shown. To the edge-strip n of each skirt-section is secured a spring-catch, o, which is composed of a single piece of spring-wire formed with an eye, 65 which receives a rivet to connect it to the strip end with spring-arms, which, on being pressed together, will enter and securely hold thereto an eye, p, forming part of a rod, q, pivoted at its other end to ears forming part 70 70 of a flanged collar, F, adjustable on the standard and secured to the standard by a set-screw. Pivoted to one of the strips n of each section E is a notched arm, r, which operates with a headed stud, s, secured to the next 75 adjacent strip n of the adjoining section to connect the said sections together, as shown. The projection l from the arms D also extends into and through sockets t, secured to the interior and lower portion of each of the waist- 80 80 sections G, which rest on the upper edge of the waistband of the skirt-sections, as shown. The neck portions of each waist-section G also has a socket, u, which receives a downwardly-extending projection, v, from an ex- 85 85 tension-arm, H, provided with slots, and at its inner end with a projection, w, also extending downward, but of less length than the projection v. The said projection w of each of the arms H enters slots in the arms x of the 90 90 collar I, fixed to the part c of the standard, and the outer ends of the said arms x have projections y, which enter the slots in the arms H, and connect them to the arms x of the collar I in the same way that the arms D are 95 95 connected to the arms h of the collar C. The said arms h and x are each to have the sizes to which the form can be adjusted marked on them to facilitate the changing of the form from one size to another. To the upper portion of the standard is applied a knob, K, pro- 100 100 vided at its bottom with a flange, a', which

bears on the arms II. Near the top of the standard is a stud, b' , which projects beyond the periphery of the standard, and in the knob is a groove, c' , extending from the bottom of the flange up to a chamber, d' , in the upper part of the knob. When the waist and the neck of the form have been adjusted to the required size, the knob is applied to the standard and borne down on the arms II to make them bear on the arms x . Then the knob is turned on its axis, so as to cause the stud b' to bear on the shoulder e' , which will prevent the knob from rising, and the various parts of the form will then be securely held to the standard.

From the above it will be seen that the dress-form hereinbefore described is provided with means of adjustment to increase or diminish its size, as may be required; and also, owing to the construction and manner of arranging and connecting the various parts, they can be readily disconnected and packed in a space of about quarter the size of that occupied by the form when set up ready for use, and will thus be in a much more convenient shape to transport than the dress-forms heretofore in use.

Having described my invention, what I claim is—

30 1. In a dress-form, the combination of the standard made in sections detachable from each other and from the foot, as described, with the flanged collar C, secured to one of said sections and provided with arms h , slotted and having at their outer ends projections i , and the skirt-sections provided with the slotted arms D, the projections i being to enter the slots in the arms D, and the arms D having the projections k to enter the slots in the arms h , all essentially as shown and set forth.

2. In a dress-form, the combination of the standard made in sections detached from each other and from the foot, as described, with the flanged collar C, secured to one of said sections and provided with arms slotted and having the projections i , and the skirt-sections having the extension-arms D, also slotted and provided with the projections k and l , the former, k , to enter the slot in the arms h , and

the latter, l , to enter sockets in the skirt-section and waist-sections of the form to support the same, all essentially as shown and set forth.

3. In a dress-form, the standard made in sections detachable each from the other, the collar C, fixed to one of the said sections and provided with arms h , slotted as shown, and having the projections i , in combination with the skirt-sections provided with the arms D, slotted and having the projections k and l , the sockets m , and with the notched arms r and headed studs s for connecting the said sections to each other, all substantially as shown and set forth. 65

4. The knob K, provided with the flange a' , and having a passage through it to receive the upper end portion of the standard, also a groove, c' , leading out of said passage, and a chamber, d' , communicating with said passage and groove, in combination with the standard provided with the stud b' , and having fixed to it the collar I, with the slotted arms x and projections y , the slotted arms H, having the downward projections v and w , the former entering the sockets u in the form-sections and the latter the slots in the said arms x , the flange of said knob bearing on said arms II, and the stud b' resting on the bottom of chamber d' , all substantially as shown, and for the purpose described. 70

5. In a dress-form, the standard-made sections, detachable each from the other and from the foot, for the purpose described, the collar C, fixed to one of said sections and provided with arms slotted, as shown, and having projections i , and the arms D, slotted, and having the projections k and l , in combination with the skirt-sections provided with sockets m and spring-catches o , the rods q , pivoted to a collar on the standard and connected to the said spring-catches, and the said collar F, adjustable on the standard, all essentially as shown and set forth. 85

In testimony whereof I affix my signature in presence of two witnesses.

FREDK. W. BROWN.
